GARMENT SUPPORTING MEANS

Robert Temple, Chevy Chase, Md.

Application November 23, 1945, Serial No. 630,175

15 Claims. (Cl. 2—311)

1

The present invention relates to new and useful improvements in garment supporting means, and more particularly to such improvements in supporting means which may be in the form of a band adapted to surround and engage a part of the body of the wearer for supporting garments of various types.

In general, the invention is concerned with the provision of a garment supporting band which may be in the form of a garter adapted to snugly engage a part of the body of the wearer in order to thereby support the garment. The garter band may be formed as a part of the garment to be supported or it may be adapted to be separably attached thereto. In either case, the gripping action of the band is independent of elastic threads or material such as are commonly employed in stretchable elastic or rubber garters. Hence, the supporting band of the present invention may be made of inelastic materials, although elastic materials may be incorporated therein when desired. More specifically, and as illustrated, the invention is concerned with the provision of a garter band which is well adapted for use in supporting limb covering apparel, such as stockings, socks, gloves and the like, although it is by no means limited to such uses.

An object of the present invention is to provide a supporting band which is constructed and arranged so as to become circumferentially contracted into garment supporting position upon relatively slight axial elongation or extension thereof.

Another object of the invention is to provide a supporting band of the above type which is particularly well adapted to initially stretched and tight fitting garments, such as a stocking, which is inherently elastic so that the initial stretching thereof on the leg of the wearer will result in a constant downward pull on the supporting band, thus tending to maintain the band in contracted gripping contact with the leg or other part of the body of the wearer.

A further object of the invention is to provide a supporting band of the above type which consists at least in part of a plurality of interwoven elements which are arranged in such diagonal relationship that a very slight effort to axially elongate the band will result in substantial inward or radial contraction thereof.

2

The above and other objects of the invention will in part be obvious and will be hereinafter more fully pointed out.

In the accompanying drawings:

5 Fig. 1 is a side view of a stocking showing the supporting band formed as a part thereof and in non-supporting position on the leg of a wearer.

Fig. 2 is a view, similar to Fig. 1, but showing the band in longitudinally extended and leg gripping position to support the stocking.

Fig. 3 is a fragmentary detail showing a supporting band made of a plurality of strip-like elements and in non-supporting position.

Fig. 4 is a view, similar to Fig. 3, but showing the relative positions of the strip elements in garment supporting position.

Fig. 5 is a view, similar to Fig. 3, but showing a modified form of strip element, each consisting of a plurality of strands.

Fig. 6 is a fragmentary and somewhat diagrammatic view showing a further modified form of band.

Fig. 7 is an enlarged fragmentary detail view showing the way in which the free ends of the strip-like elements may be interlocked.

Referring more in detail to the accompanying drawings, and particularly to Figs. 1 and 2 thereof at this time, the invention is illustrated in connection with a stocking of any suitable type which includes a leg portion 10 and a top reinforcing band portion 11. The supporting band or garter element of the present invention is somewhat diagrammatically shown in Figs. 1 and 2 as including sets of interwoven strands or threads 14, 14a, the strands 14 being substantially parallel to each other and disposed diagonally with respect to the strands 14a which are also substantially parallel to each other. The strands or threads may be made of any suitable material which may be substantially inelastic. The lower ends of the strands are suitably secured to the band portion 11 of the stocking and the upper ends thereof may be tied or otherwise suitably secured to a band 15. This band 15 may be elastic and merely serves as an attaching element for properly maintaining the strands in position.

The relative angular disposition of the strands 14, 14a in the non-gripping position of Fig. 1 is such that each strand is peripherally separated.

50 Thus, to facilitate putting on the stocking, the

band 12 may be peripherally extended if no longitudinal pull is exerted thereon. As the stocking is stretched over the leg, it is longitudinally stretched against its inherent resiliency so that it will tend to move downwardly on the leg. The band 12 is now extended upwardly on the leg and this upward pull on the strands 14, 14a will, by reason of the diagonal arrangement of the strands, cause the band to contract and press against the leg of the wearer, thus serving as a leg gripping support for the stocking. It will be seen that the longitudinal or axial pull exerted on the band 12 will cause the strands 14, 14a to closely approach one another as suggested in Fig. 2, and the entire band 12 will be radially contracted to grip the leg of the wearer. After the original setting of the stocking and the band 12, it should be noted that the downward pull of the stretched stocking on the band 12 is of sufficient force to maintain the original setting of the garter band. Thus, no elastic garter elements are required and the tight stretching of the stocking due to its inherent elasticity, will tend to maintain the band 12 in contracted and gripping relation to the leg of the wearer.

A preferred construction of the supporting band is shown fragmentarily in Figs. 3, 4 and 7, wherein the band 16 consists of a plurality of flat strip-like elements 17, 18 diagonally interwoven with respect to each other. In this form of the invention, the strips may be somewhat elastic, if so desired, as there is substantial surface contact between the lapping portions of the strips and less longitudinal pull is required to cause the band to be contracted into gripping position. The strips may be made of any suitable material but a material, such as a copolymer vinyl or nylon plastic, is considered to be highly satisfactory. As previously pointed out, the lower ends of the diagonally arranged interwoven strips 17, 18 may be secured to the reinforcing band 11 of the stocking and the upper ends may be secured to any type of band. However, the individual strips may be looped upon themselves with both ends secured to the band 11, as shown in Fig. 7, so that the upper looped ends can remain free and uncured. As shown in Fig. 3, there are spaces between the strips which may be widened when the stocking is being put on. However, when the upper edge of the supporting band 16 is pulled upwardly against the action of the stretched stocking, the band 16 will be contracted by relative sliding of the strips to grip the leg of the wearer and the strips 17, 18 will assume the closed positions shown in Fig. 4, these positions being the contracted leg gripping positions. The stretched stocking will maintain the band 16 in supporting position. The spacing between the interwoven elements of the garter, or the looseness of the weave is an important factor in controlling the degree of elongation and consequent peripheral contraction of the garter band.

In the form of the invention shown in Fig. 5, the band 16a is somewhat similar to that shown in Figs. 3 and 4, except that each individual diagonally arranged strip 17a, 18a consists of a plurality of separate strands 19 of suitable material. The action of the band 16a is otherwise the same, but greater stretching and contracting will be permitted. As in the case of the strips shown in Fig. 3, there is substantial surface contact between the lapping portions of the strips 17a, 18a so as to effect greater gripping action with less pull.

A further modification is shown in Fig. 6 in

which the band 20 is illustrated as including areas 21 of a multiplicity of structural elements such as threads, strips or the like, which may be separated by areas 22 of elastic material or construction. The areas 21 are constructed according to one of the supporting bands heretofore described but the elastic areas 22 permit greater stretching of the band as a whole. This band may be secured directly to the stocking as previously described, or it may serve as a separate garter element in which case the areas 21 should be equipped with suitable releasable fasteners 23 (only one being shown) adapted for attachment to the reinforcing band of the stocking or other garment to be supported. The downward pull of the stocking acting through the fasteners 23 will tend to shorten or contract the peripheral length of the areas 21 so as to effect a gripping action against the legs of the wearer in the manner pointed out above.

The relative diagonal disposition of the interwoven elements of the supporting bands is such as to give the requisite amount of gripping action or contraction as the result of a predetermined extension of the band axially thereof, and will depend to some extent on the material used, as well as the character of the garment to be supported. For most uses, the materials and arrangement of parts should be so selected that a slight downward force, such as that exerted by a stocking stretched on the leg of a wearer, is sufficient to maintain an originally set axial extension of the garter band so that the normal pull of a stocking while being worn will maintain the band contracted in garment supporting position. In some instances it may be desirable to have some stretchable elastic connection, such as an elastic band, between the garter band and the garment in order to maintain or augment the longitudinal strain on the garter band. The pull on the band will maintain the frictional holding contact between the body or the limb of the wearer and the lapping surfaces of the diagonal elements of the garter band.

While certain forms of the invention have been shown for purposes of illustration, it is to be clearly understood that various changes in the details of construction and arrangement of elements may be made without departing from the scope of the invention as set forth in the appended claims.

I claim:

1. A garter member for an inherently elastic garment which is stretched over the body or limb of the wearer, and comprising an annular band adapted to surround the body or limb of the wearer, said band being constructed of lapping and intersecting elements arranged so as to become peripherally contracted upon axial extension thereof, and adapted to be connected to the stretched garment whereby the elastic pull of the stretched garment on the garter member will maintain the band in contracted body or limb gripping position.

2. A garter member, as claimed in claim 1, wherein the band consists of a plurality of diagonally disposed interwoven strips having substantial surface contact between the lapping portions thereof.

3. A garter member, as claimed in claim 1, wherein the band includes peripherally spaced sections formed of diagonally interwoven elements arranged to peripherally contract upon longitudinal extension thereof.

4. A garter member, as claimed in claim 1,

wherein the contractible band includes a plurality of diagonally arranged interwoven elements of substantially inelastic material.

5. A garter member, as claimed in claim 1, wherein the band includes diagonally interwoven substantially flat groups of strand elements having substantial surface contact between lapping groups to provide frictional holding surfaces.

6. In a garment adapted to be stretched over a portion of the body of the wearer, the provision of supporting means engaging and maintaining the garment in substantially the original stretched condition thereof over the body portion of the wearer and consisting of sets of diagonally disposed relatively movable lapped elements arranged for relative sliding in the lapped areas and effective to contract upon the body of the wearer upon application to said elements of forces acting in the direction of the forces of the stretched garment.

7. A garter for garments having inherent elasticity and adapted to be stretched over a portion of the body of the wearer, and comprising a deformable band of relatively slidible interwoven elements adapted to be connected to the garment and arranged to contract upon the body of the wearer upon application to said elements of the reaction forces of the stretched garment whereby the stretched garment will maintain the garter in supporting position.

8. A garment adapted to be stretched over a portion of the body of the wearer and comprising a body covering portion, and a garter member for supporting the garment around the periphery thereof and including relatively slidible elements disposed angularly and lapped so as to contract against the body of the wearer upon application of forces reactive to the stretched condition of the garment.

9. A garment, as claimed in claim 8, in the form of hosiery wherein the garter member includes diagonally interwoven elements slidable relative to one another and adapted to contract against the body of the wearer upon the application thereto of forces reactive to the forces exerted by the stretched garment.

10. A garment support adapted to surround the body or limb of the wearer and to be attached to the garment and comprising a deformable annular band including a plurality of interwoven elements crossed and slidable relative to one another so as to effect peripheral contraction of the band upon limited axial extension thereof whereby the band will grip the body or limb of the wearer to support the garment under influence of the reactive forces within the garment acting on the support.

11. A garment support adapted to surround the body or limb of the wearer and to be attached to the garment and comprising a deformable annular band including sets of intersecting and lapping elongated elements diagonally and slidably arranged with respect to each other for effecting peripheral contraction of the band upon slight longitudinal extension thereof whereby to

grip the body or limb of the wearer in supporting the garment under influence of the reactive forces within the garment acting on the support.

12. A garment support adapted to surround the body or limb of the wearer and comprising a substantially inert deformable annular band including interwoven lapped and substantially inelastic elongated elements arranged for relative shifting therebetween in the lapped areas and effective to peripherally contract the band upon longitudinal strain thereon whereby the band will grip the body or limb of the wearer to support the garment, and said band having said elongated elements substantially free at one edge thereof but adapted to be connected to the garment at the opposite edge thereof.

13. A garment support as claimed in claim 12, wherein the elongated elements are doubled back upon themselves and interconnected at the free edges thereof.

14. In a stocking having a body portion provided with foot and leg sections, the provision of a garter section in the form of an annular band having the lower edge thereof connected to the leg section, said garter section including sets of diagonally disposed strand elements with the elements of each set alternately overlapping and underlapping elements of another set and said elements being relatively slidable with respect to each other and the angular disposition thereof being such as to effect contraction of the garter section under influence of the longitudinal pull exerted by the body portion on the said elements.

15. A garter for supporting a garment adapted to be stretched over a portion of the body of the wearer and comprising an annular band consisting of peripherally spaced elastic sections separated by connected inelastic sections, said inelastic sections formed of diagonally interwoven elements arranged to peripherally contract upon longitudinal extension thereof, and connector members secured to said inelastic sections and adapted to be connected to the garment whereby the pull of the garment through said connector members will contract said inelastic sections with resultant gripping of the band upon the body of the wearer.
